LIQUID-GAS-PHASE CONTROL

Robert D. Cowherd, Metairie, La., assignor to
 The Bristol Company, Waterbury, Conn., a corporation of Connecticut

Application May 21, 1942, Serial No. 443,895

6 Claims. (Cl. 137—78)

1

This invention relates to automatic control in the operation of pulp-digesters or other apparatus wherein under abnormal conditions a liquid may enter a conduit or a pipe line or a reaction vessel whose content is normally restricted to a gaseous medium. While there is no intention of limiting the utility of the invention to one specific type of apparatus, yet because of its special adaptability to certain processes in the manufacture of paper, the invention will be described in its application to a pulp-digester.

In the manufacture of wood pulp it is customary to charge a closed vessel known as a digester with a quantity of wood chips and suitable chemicals and then to set up a reaction by the admission of steam or other heating agent. In the course of this process certain gases are given off; and it is usual to vent these from the top of the digester in a manner to maintain predetermined pressure values within the digester. Due to the chemical characteristics of the solution or liquor within the digester there is a tendency toward foaming, with the result that under certain conditions some of the solution may be drawn off with the gas, thus depleting the chemical content of the digester and interfering with the proper conversion of the pulp. Automatic control of the venting of gases is not new; and it is customary to equip digesters with instrumentalities which will regulate a valve in the vent pipe in accordance with predetermined pressure settings. Such devices, however, take no cognizance of the condition of the fluid being vented, and will as readily vent the digesting liquor as the gaseous products of the reaction. It is recognized, also, that there are available various phase-discriminating devices, lying in the general category of "steam traps," operating for the most part either on a gravimetric principle or on a basis of relative temperature of a liquid and its vapor; but, as the former require intricate weighing mechanisms and are inherently slow in their action, and as the factor of actual temperature is not necessarily an element in the desired discrimination, such devices are not suited to the objects of the invention.

It is an object of this invention to provide means whereby an automatic control of the venting of the products of the reaction will discriminate between the gas phase and the liquid phase of said products independently of the temperature of the same.

It is a further object to provide means whereby said products in their gaseous form will be freely vented, while liquids will be effectively retained in the digester.

2

It is a further object to provide means for automatically clearing the vent pipe of foam or liquid products when such find their way into said pipe, and leaving the pipe free for the exit of gaseous products.

In the carrying out of the invention it is proposed to provide in the vent pipe of a digester or similar piece of apparatus a device which will respond to characteristics wherein the gas phase of the vented products will differ from the liquid phase, to effect control of the venting valve and also of the admission of a medium for flushing out the vent pipe. It is proposed that the sensitive device be made responsive to the energy-transmitting properties, rather than the energy content, of the products being vented from the digester; and for this purpose discrimination between gas and liquid phases is made on a basis of their relative electrical conductivity or their transparency to light.

In the drawings:

Fig. 1 is a diagrammatic representation of a pulp-digester showing the invention applied to the control of relief of internal pressure by regulating the outflow of products of the reaction.

Fig. 2 is a diagram showing partly in section the details of the sensitive element as based on electrical conductivity of the effluent.

Fig. 3 is a diagram showing in section the details of the sensitive element as based on the light-transmitting properties of the effluent.

Fig. 4 shows in section certain elements which may be substituted for corresponding parts in the embodiment shown in Fig. 3.

Fig. 5 is a diagram showing partly in section a form of electrode adapted to utilize the property of electrical capacitance.

Fig. 6 is a bottom elevation of said electrode.

Referring now to the drawings, the numeral 10 designates a pulp-digester into which mixture of wood chips and suitable chemicals may be charged through an opening in the top, which is afterwards sealed by a cover plate 11 secured to place by means of bolts 12. A conduit 13 provides for

the admission of steam to the lower part of the digester. A conduit 14 connected near the top of the digester provides for the venting of products of the internal reaction to the atmosphere, or to a receptacle not shown in the drawings whereby certain valuable constituents of said products may be salvaged. The venting of said products is regulated by a diaphragm valve 15 inserted in the conduit 14 and subject to actuation by air admitted to its operating element through a conduit 16. Said valve 15 is of the "reverse-acting"

type, its action being such that increase of pressure in the conduit 16 tends to increase the degree of opening of the valve, and vice versa. A pipe 17 provides for the admission of steam or other suitable agent to the conduit 14, whereby the part of the conduit in immediate proximity to the digester may be flushed out and cleared of accumulated liquid or semi-liquid material, and any tendency toward foaming of the digester contents suppressed. A diaphragm valve 18 of the reverse-acting type is inserted in the pipe 17 and has its operating element placed in communication with a conduit 19 whereby air pressure in said conduit will cause said valve to be opened.

A controlling instrument 20 which may expediently be of the type fully set forth and disclosed in U. S. Letters Patent No. 1,880,247, granted October 4, 1932, to Griggs and Mabey, is adapted to regulate in the conduit 16 the pressure of air derived from the source 21, in response to changes in pressure within the digester 10, as communicated to said instrument 20 through a conduit 22. The connections and adjustments of the instrument 20 and associated elements are made such that under normal operating conditions said instrument, acting through the medium of air in conduit 16, tends to adjust the valve 18 in a sense to regulate the rate of escape of gaseous products of the reaction to maintain a predetermined constant pressure within the digester 10.

Inserted in the conduit 14 at a point near its emergence from the digester 10 is an insulated electrode 23, which may expediently be provided by the use of a spark plug 24 of the type commonly used for the ignition of internal combustion engines. An electro-responsive instrument 25 is connected in circuit with the electrode 23 and the conduit 14 and adapted to control the flow of fluids in conduits 14 and 17 by means which will be more fully understood by reference to Fig. 2 taken in conjunction with Fig. 1.

The controlling instrument 25 shown in Fig. 2 may expediently be of the form fully set forth and described in U. S. Letters Patent No. 1,979,330, issued November 6, 1934, to G. W. Kuntry. This instrument includes an electro-sensitive device 26, which may be the conventional permanent-magnet moving-coil class of galvanometer, in which a movable coil 27 placed between opposite magnetic poles N, S, is caused to deflect through a limited angle when electric current is passed through said coil. The deflection of the coil 27 causes a movable contact 29 to be brought into electrical engagement with a stationary contact 30. Electrical connection whereby the instrument 25 is made responsive to current passing between the insulated electrode 23 and the conduit 14 is provided by the following means: A conductor 31 forming one side of a source of A.-C. supply is connected to the electrode 23. A conductor 32 forming the other side of said source is connected to one terminal of the primary winding of a transformer 33, the other terminal of said winding being connected by means of a conductor 34 to the conduit 14. The secondary winding of transformer 33 is connected to two opposite terminals of a 4-terminal rectifying bridge 35. The other two terminals of said bridge are connected to the coil 27, the connections being such that upon the passage of alternating current through the primary winding of the transformer 33, the secondary current of the transformer will be rectified by the bridge 35, causing a representative direct current to

flow in the coil 27. A solenoid valve 36 is connected between the conduit 18 and the source of air supply 21 (or an independent source if desired), and is electrically wired to have its actuating winding energized from the conductors 31 and 32 (or an independent electrical source if desired) in series with the contacts 29 and 30 in such a manner that when said solenoid is energized by the closing of said contacts, the valve 36 will be opened, and will be closed when said solenoid is deenergized.

Inserted in the conduit 16 is a diaphragm valve 38 of the "three-way" type, having its operating element in communication with the conduit 19, and being arranged in such a manner that when no pressure exists in the conduit 16 said valve provides a direct connection through the conduit 16 between the regulating instrument 20 and the control valve 18; and when pressure is applied through the conduit 16, communication between said instrument and control valve is interrupted, and the operating element of the latter vented to the atmosphere.

The operation of the device as thus far disclosed is as follows: Upon the digester being charged and steam admitted through the conduit 13, a reaction is set up in which there are given off certain gaseous products which accumulate in the upper part of the digester. As the pressure due to accumulation of these gases attains a predetermined value, the instrument 20, acting in response to said pressure, tends to increase the pressure in the conduit 16, and thus adjust the valve 18 to allow a certain quantity of said gases to be vented through the conduit 14, whereby said pressure will be relieved. As hereinbefore pointed out, there sometimes develops a tendency for liquid components of the contents of the digester to be carried over with the vented gases and discharged through the conduit 14. The insulated electrode 23 projecting into the interior of the conduit 14 is surrounded by the reaction products which are being vented through said conduit. So long as normal conditions exist and these products are gaseous in their nature, the electrical resistance from the electrode 23 to the conduit 14 is extremely high, so that no appreciable current passes through the circuit of which said electrode and conduit form a part. Under this condition no current will pass through the coil 27 in the instrument 25, and the contacts 29 and 30 will remain separated, leaving the actuating winding of the solenoid valve 36 in a de-energized condition and said valve closed. Thus there will be no air pressure applied to either of the diaphragm valves 18 and 38, with the result that the valve 18 will remain closed, preventing the admission of steam through the conduit 17, and the valve 38 will remain in a position to allow free operative communication between the regulating instrument 20 and the diaphragm valve 18.

In the event of a portion of the liquid contents of the digester 10 being carried into the conduit 14, the relatively high electrical conductivity of said liquid will provide a path between the electrode 23 and the walls of the conduit 14, thus permitting current to flow between the conductors 31 and 32 through the primary winding of the transformer 33. This in turn will set up a current in the secondary winding of said transformer, which, passing through the rectifying bridge 35, will cause a unidirectional current to pass through the galvanometer coil 27 in the instrument 25, deflecting the contact 29 into engagement with the

contact 30 and thereby completing the circuit of which said contacts form a part. Current will then pass between the wires 31 and 32 through said contacts and associated conductors and the winding of valve 36, causing said valve to be opened, admitting air from the source 21 to the conduit 19. Air pressure in the conduit 19 being applied to the operating element of the valve 38 will cause said valve to interrupt communication through the conduit 16 between the controller 20 and the valve 15 and vent the latter to the atmosphere, causing said valve 15 to be closed. At the same time air pressure in the conduit 19 acting upon the valve 18 will cause the same to be opened, admitting steam through the pipe 17 to the conduit 14 and blowing back into the digester 10 any liquid or semi-liquid material which may be present in said conduit, thereby flushing said conduit for further operation, and suppressing the reaction. Upon the clearing of the electrode 23 from conducting matter, the electrical path between said electrode and the walls of conduit 14 will be interrupted, thus terminating the flow of current through the transformer 33, the rectifier bridge 35 and the coil 27, whereupon the contact 29 will be separated from the contact 30, the solenoid of the valve 36 de-energized, the valve 38 closed, and the control system caused to revert to its normal operating condition.

In Fig. 3 is shown an alternative form of the invention in which discrimination between normal operating conditions and abnormal conditions is based on the light transmitting characteristics of the effluent. A body part or fitting 40 is inserted in the conduit 14 at a point near its emergence from the digester 10. The part 40 provides a passage for the contents of the digester 10, and is fitted with opposed laterally located windows 41, 42 formed of glass or other suitable transparent material, clamped in place by suitable bolts 43, 44, and having gaskets 45 and 46 whereby a tight seal is effected. Outside the window 41, in a suitable housing 47, is placed a light source 48, which may expediently be a small incandescent bulb energized from an electric power supply not shown in the drawings. Outside the window 42 is placed a photosensitive cell 49, which may be of the blocking-layer or so-called "Photronic" type, adapted to become a source of electromotive force when exposed to radiant energy projected from the light source 48 through the windows 41 and 42 and the intervening space within the body part 40. A controlling instrument 50, mechanically similar in all respects to the instrument 25 shown in Fig. 2, is connected to operate the solenoid valve 36. The galvanometer element of the instrument 50 is adapted for actuation by, and is directly connected through a two-conductor circuit 51 to, the photosensitive cell 49, the connection being made in such a manner that when said cell is energized the electric current derived therefrom, passing through the galvanometer element of the instrument 50, will tend to maintain the controlling contacts of said instrument in an open condition, allowing the solenoid valve to be de-energized.

Under normal operating conditions the gaseous effluent from the digester will offer no obstruction to the passage of light from the source 48 to the cell 49, with the result that the galvanometer element of the controller 50 will be energized, and the solenoid valve 36 will remain closed. In the event of an abnormal condition developing and the liquid content of the digester finding its way through the conduit 14 into the fitting 40, this "black liquor," being normally opaque, will ob-

struct the flow of light, causing the cell 49 to reduce the potential of its output, de-energizing the galvanometer of the instrument 50, and allowing the contacts of that instrument to be closed, energizing and opening the solenoid valve 36, and thus applying air pressure to the operating elements of the valves 18 and 38 to introduce influences to meet the abnormal situation as hereinbefore set forth. Upon cessation of flow of black liquor in the body part 40 the cell 49 will again become active, the contacts in the instrument 50 will be opened, the valve 36 closed, and the system will revert to its normal operating condition.

The operation of the device in response to light conducting properties of the effluent, as thus far described, is based on the fact that the black liquor in a digester is opaque to light. In the event of it being desired to utilize the principles of the invention in connection with a control process wherein the liquid effluent is transparent, and in which the interposition of a body of such liquid between the windows 41 and 42 might not materially obstruct the passage of light, the windows may be given a curved conformation as shown at 52 and 53 in Fig. 4. With this construction, so long as there is a body of clear gas between the windows, the passage of a light beam through the fitting 40 will not be materially disturbed by the curvature of the windows. If, however, a body of clear liquid replaces the gaseous content within the fitting 40, the curved surface of said liquid as defined by its contact with the curved windows, will cause said body of liquid to act as a lens. As illustrated in the drawings, the windows 52 and 53 are shown as being inwardly convex, so that a mass of liquid between them will function as a bi-concave lens, causing the light rays to diverge to an extent that the photocell will no longer receive illumination to cause it to develop sufficient power to open the contacts in the controlling instrument 50. It is possible, however, to replace the inwardly convex windows by outwardly convex windows, in which case the relative disposition of the photocell and the light source so that the refractive action of the body of liquid will bring the light rays to a focus at a point where the photocell will not be strongly excited, becomes a matter of longitudinal adjustment.

In the form of the invention shown in Figs. 5 and 6, use is made of the principle of the electrolytic capacitor in which the property of capacitance is due to the presence of an insulating film of molecular thickness formed by the action of certain electrolytes upon the surface of certain film-forming materials. It is a unique property possessed by some metals, such for example, as tantalum, that when immersed in certain electrolytes and subjected to a difference of potential, there will be formed on the surface of one of said plates a film of insulating oxide which manifests the property of uni-lateral conduction, and which by virtue of its molecular thickness serves to provide the dielectric layer for a capacitance of relatively high value between the plate and the electrolyte. When two such plates are used, and an alternating potential applied, the layers on the respective plates function as dielectrics toward the respective half-waves of the potential, so that a complete bilateral capacitor is formed.

In applying this property to the purposes of the invention, an electrode 60, adapted to be threadedly inserted into a conduit 14 in the same manner as the spark plug 24 shown in Fig. 2, in-

cludes two plates 61 and 62, the former being attached to the metallic part of the body electrode 60 and thereby grounded to the conduit 14 and the latter attached to the insulated part of said electrode, whereby electrical connection may be independently made to an outside circuit. The plates 61 and 62 are mutually juxtaposed and so positioned that when the effluent carried by the conduit 14 is in a liquid state it will immerse both of said plates, so that upon application of a suitable electrical potential between them they will acquire the properties of capacitor plates. By virtue of the extremely high capacitance in proportion to the physical dimensions of the plates, it is found that the charging current which passes through such a capacitor is, for most values of alternating current, comparable with, or higher than, that which would pass due to ordinary electrical conductivity.

It is thus made possible to utilize the relatively simple circuit shown in Fig. 5, wherein a relay 65 is directly actuated by a coil 64 and includes a set of normally open contacts 65 connected in series with the solenoid valve 36 and a source of alternating current supply 66. The coil 64 is connected across the supply 66 in series with the electrode 60, whereby passage of current between the plates 61 and 62 will cause said coil to be energized. Tests have shown that the performance of this type of electrode is extremely sensitive, and that as soon as an actual connection between the plates is made by a suitable electrolyte, of which the black liquor formed in a pulp digester is an excellent example, there is a definite threshold action, whereby the relay 64 is operated to close the contacts 65 and bring the protective apparatus into action immediately upon the appearance of the liquid phase of the effluent of the pulp digester in the conduit 14.

The term "liquid" as employed in the foregoing specification and in the ensuing claims includes material of semi-liquid character, i. e., mixtures of liquid and solid material.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. In apparatus for regulating the venting of effluent through a conduit extending from a processing container evolving a normally gaseous effluent, means for discriminating between gaseous and liquid phases of said effluent in said conduit, control means sensitive to said discriminatory means in response to the presence of a liquid phase in said effluent, and means brought into action by said control means in response to the presence of said liquid phase for controlling the admission of a flushing fluid to said conduit to flush the contents thereof back against the normal flow direction.

2. In apparatus for regulating the venting of effluent through a conduit extending from a processing container evolving a normally gaseous effluent, means for discriminating between gaseous and liquid phases of said effluent in said conduit, control means sensitive to said discriminatory means in response to the presence of a liquid

phase in said effluent, and means brought into action by said control means in response to the presence of said liquid phase for blocking said conduit to terminate said venting and for controlling the admission of a flushing fluid to said conduit to flush the contents thereof back against the normal flow direction.

3. In combination, a processing container adapted to contain an electrically conducting liquid and vapor from the same, a venting conduit adapted to carry off effluent from said container, means comprising an electrode in said conduit for impressing an electromotive force across a portion of said effluent, normally open valve means in said conduit, means for directing a flushing fluid into said conduit, said electrode being positioned in the path of said flushing fluid, normally closed valve means in said directing means, and control means brought into action in response to flow of electric current through said electrode when the latter is contacted by liquid in said effluent for closing the valve means in said conduit and opening the valve means in said directing means.

4. In combination, a processing container adapted to contain an electrically conducting liquid and vapor from the same, a venting conduit adapted to carry off effluent from said container, means comprising an electrode in said conduit for impressing an electromotive force across a portion of said effluent, means for directing a flushing fluid into said conduit, normally closed valve means in said directing means, and control means brought into action in response to the flow of electric current through said electrode when the latter is contacted by liquid in said effluent for opening said valve means to admit flushing fluid to said conduit, said electrode being positioned between said directing means and said container.

5. Apparatus for preventing the flow of liquid through a conduit in which either a liquid or a gas may flow, said apparatus comprising means for impressing upon the flowing fluid in said conduit a force tending to cause a different amount of energy to pass from an external source through said fluid when the flowing fluid is a liquid than when it is gas, means sensitive to the flow of energy through said fluid, and means controlled by said sensitive means in response to passage of said energy through a liquid for controlling the admission of a flushing fluid to said conduit to flush the contents thereof back against the normal flow direction.

6. Apparatus for preventing the flow of liquid through a conduit in which either a liquid or a gas may flow, said apparatus comprising means for impressing upon the flowing fluid in said conduit a force tending to cause a different amount of energy to pass from an external source through said fluid when the flowing fluid is a liquid than when it is gas, means sensitive to the flow of energy through said fluid, means responsive to operation of said sensitive means upon passage of said energy through a liquid for cutting off flow of said fluid in the normal flow direction, and means responsive to said operation of said sensitive means for controlling the admission of a flushing fluid to said conduit to flush the contents thereof back against the normal flow direction.

ROBERT D. COWHERD.
